US0D1045778S

(12) **United States Design Patent** (10) Patent No.: **US D1,045,778 S**
(45) Date of Patent: ** Oct. 8, 2024

(54) **BATTERY CHARGER**

(71) Applicant: **Krystal Gabel**, Shelby, NE (US)

(72) Inventor: **Krystal Gabel**, Shelby, NE (US)

(**) Term: **15 Years**

(21) Appl. No.: **29/808,916**

(22) Filed: **Sep. 23, 2021**

(51) LOC (14) Cl. **13-02**

(52) U.S. Cl.

USPC **D13/107**

(58) **Field of Classification Search**

(57) **CLAIM**

The ornamental design for a battery charger, as shown and described.

DESCRIPTION

FIG. 1 is a front perspective view of a battery charger, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right-side elevation view thereof; and,

FIG. 8 is a smaller scale of the battery charger located in a vehicle.

The broken lines showing the vehicle in FIG. 8 illustrate environment and form no part of the claimed design.

The broken lines showing the axles for supporting the fans within the battery charger in the figures form no part of the claimed design.

1 Claim, 4 Drawing Sheets
